UNITED STATES PATENT OFFICE.

RUTH E. CLEMENT, OF CAMBRIDGE, MASSACHUSETTS.

FILE.

Application filed June 22, 1923. Serial No. 647,034.

To all whom it may concern:

Be it known that I, RUTH E. CLEMENT, a citizen of the United States, and a resident of Cambridge, in the county of Middlesex and State of Massachusetts, have invented an Improvement in Files, of which the following description, in connection with the accompanying drawings, is a specification, like characters on the drawings representing like parts.

This invention relates to a novel and improved paper file for the vertical filing of large papers such as maps, plans, drawings and the like. The invention will be best understood by reference to the following description when taken in connection with the accompanying drawings of one specific embodiment thereof, while its scope will be more particularly pointed out in the appended claims.

In the drawings:

Fig. 1 is a front elevation of a file exemplifying the invention, showing the roll front lowered to expose the papers;

Fig. 2 is a sectional view on an enlarged scale on line 2—2 of Fig. 1;

Fig. 3 is a sectional view on line 3—3 of Fig. 2; and

Fig. 4 is a sectional view on line 3—3 of Fig. 2, but showing the papers projected through the opening in the front of the cabinet for inspection and removal.

Referring to the drawings and to the embodiment of the invention which is selected for exemplification, there is shown a vertical file comprising a series of sheets 6 suspended from hangers 7 which are attached to an appropriate carrier, herein comprising a rod 8, onto which the hangers 10 are hooked. Herein, each sheet is conveniently attached to its hanger by being provided with an eyelet 9 which receives a hook 10 presented by the hanger. In removing a given sheet from the carrier, it may be unhooked from its hanger very readily without the necessity of removing the latter from the carrier.

The carrier is guided horizontally in the general direction of the sheets by appropriate guides 11 and 12 at each end of the carrier, and to minimize frictional resistance to the travel of the carrier, in the present example it is provided with grooved wheels 13 which travel on the upper and lower rails 14 and 15 presented by the guides 11 and 12, respectively, these wheels being mounted to

turn on the terminal portions of the rod 8.

Forward and backward movement of the carrier along its guides is conveniently accomplished through the use of a rod 16 attached to the carrier and extending in the direction of the guides, said rod being provided at its forward end with a knob 17 which may be grasped to operate the carrier. The rod extends through and is guided by a guide 18 conveniently presented by a frame which also supports the guides for the carrier. The guide 18 limits forward movement of the carrier (see Fig. 4) as well as rearward movement thereof (see Fig. 2). In the present example, this frame is presented by a casing or cabinet having a top 19, a rear wall 20 (see Fig. 2) and two side walls 21. The front of the cabinet presents an opening 22 (see Fig. 1) which is normally closed by a roll front 23, the latter, when dropped as shown in Fig. 1, being below edges of the sheets, whereby the sheets may be projected through the opening for inspection and removal from their respective hangers by simply grasping the knob 17 and pulling the carrier forward from the position shown in Fig. 2 to that shown in Fig. 4. When this is done, a considerable expanse of each sheet can be inspected thereby to identify the particular sheet wanted, and the selected sheet can be detached from the carrier most conveniently and expeditiously without disturbing the remaining sheets. The convenience of this arrangement will be readily appreciated.

Having thus described one embodiment of the invention but without limiting myself thereto, what I claim and desire by Letters Patent to secure is:

1. In a file, the combination of a housing presenting a front opening, a sheet carrier mounted in said housing, guiding means for said carrier permitting movement thereof toward and from said opening, a series of sheets, a series of hangers on said carrier for suspending said sheets with their edges directed toward said opening, said sheets extending forward beyond said hangers and beyond said carrier, pull actuated means directly connected to said carrier and accessible from the front of said housing for moving the carrier back and forth in said guiding means, and means limiting the forward movement of said carrier so that the forwardly extending edges of said sheets shall project through said opening beyond

and unobstructed by said carrier, whereby said sheets are presented for inspection and manipulation without obstruction.

2. In a file of the class in which sheets are filed in generally parallel planes, the combination of a series of hangers by which the sheets are suspended, a carrier to which said hangers are attached, guiding means by which said carrier is guided horizontally 10 in the general direction of said sheets, a frame supporting said guiding means, and a pull rod attached to said carrier and extending lengthwise of the travel thereof for moving said carrier to and fro along said 15 guiding means.

3. In a file of the class in which sheets are filed in generally parallel planes, the combination of a series of hangers by which the sheets are suspended, a carrier to which 20 said hangers are attached, guiding means by which said carrier is guided horizontally in the general direction of said sheets, a frame supporting said guiding means, a rod attached to said carrier and extending 25 lengthwise of the travel thereof for moving said carrier to and fro along said guiding means, and a casing normally housing said sheets and presenting at its front an opening through which said sheets may be projected by pulling said rod forward, said 30 rod projecting from the front of said casing.

4. In a file of the class in which sheets are filed in generally parallel planes, the

combination of a series of hangers by which 35 the sheets are suspended, a carriage to which said hangers are attached, guides to guide said carriage horizontally in the general direction of said sheets, a pull rod extending horizontally in the general direction of the planes of said sheets and attached to said carriage to move the same along said guides, and a cabinet which normally houses said sheets and presents an 40 opening through which said sheets may be projected for inspection and removal from their respective hangers. 45

5. In a file for the vertical filing of sheets, the combination of a series of hangers for the sheets, a rod to which said hangers are attached, guides for said rod extending transversely thereof, a pull rod extending 50 transversely of and attached to the first rod, and a guide for said pull rod.

6. In a file for the vertical filing of sheets, the combination of a series of hangers for the sheets, a rod to which said hangers are attached, guides for said rod extending transversely thereof, a second rod extending 55 transversely of and attached to the first rod, and a cabinet presenting a housing for the sheets, a guide for said second rod, and an opening through which the sheets may be projected by pulling said second rod forward in its said guide. 60

In testimony whereof I have signed my name to this specification.

RUTH E. CLEMENT.
